PLATEN ROTATING MECHANISM FOR
STENOGRAPHIC TYPEWRITERS

Harrison M. Von Duyke, Wilmington, Del.

Application June 3, 1947, Serial No. 752,215

7 Claims. (Cl. 197—9)

1

This invention relates to typewriter platen mechanism, and it relates more particularly to mechanism for rotating the platen of a stenographic typewriter, with a step by step movement, so constructed and arranged that each rotative movement of the platen follows the actuation of one or more of the key levers.

The principal object of the present invention is to provide improved mechanism for operating the platen of a stenographic typewriter which will be simple and efficient in its operation.

A further object of the invention is to provide mechanism, of the character aforesaid, which will be positive in its action, yet practically noiseless.

A further object of the invention is to provide mechanism, of the character aforesaid, which will require a minimum of effort, on the part of the operator, in its actuation.

A further object of the invention is to provide mechanism, of the character aforesaid, the various parts of which are readily accessible, and which is so constructed and arranged that it may be quickly and easily taken apart and reassembled for the purpose of repair and replacement of worn or damaged parts.

The nature and characteristic features of the present invention will be more readily understood from the following description, taken in connection with the accompanying drawings forming part hereof, in which:

Figure 1 is a top or plan view of a stenographic typewriter, certain parts being removed and omitted for the purpose of illustrating platen operating mechanism embodying the main features of the present invention;

Fig. 2 is a side elevation thereof enlarged;

Fig. 3 is a transverse vertical sectional view, taken on the line 3—3 of Fig. 2, and still further enlarged;

Fig. 4 is a fragmentary sectional view, taken approximately on the line 4—4 of Fig. 3, and illustrating a preferred form of ratchet clutch employed as part of the mechanism of the present invention; and

Fig. 5 is a fragmentary sectional view, taken approximately on the line 5—5 of Fig. 3, and illustrating a portion of the link work and gearing for transmitting motion from the key levers to the platen shaft.

It should, of course, be understood that the description and drawings herein are illustrative merely, and that various modifications and changes may be made in the structure disclosed without departing from the spirit of the invention.

2

Referring to the drawings, in the particular embodiment of the invention therein shown, 10 and 11 are side plates comprising portions of the frame work of the machine. Extending across 5 between the frames 10 and 11, and projecting beyond the outer faces thereof, on each side, is a pivot pin 12 upon which the key levers 13 of the typewriter are pivoted. This pivot pin 12 also serves as a means for mounting pivoted bracket 10 arms 14 and 15, the forward ends of which are secured to and serve to support a channel bar 16. The bar 16 extends across the machine below the key levers and supports a strip of felt 17 against which the bottom edges of the key levers bear. 15 For the purpose of holding the felt member 17 against the lower edges of the key levers 13 there are provided, on each side of the machine, coil springs 18. The lower end of each of said coil springs 18 is secured to the respective bracket 15 arms 14 or 15, and the upper end of each of said coil springs is secured to a pin member 19 which is mounted in one of the side plates of the machine.

The bracket arm 14 on one side of the machine 25 is provided with a projecting arm 20 having a tooth 21 at the outer end thereof. The tooth 21 engages a recess 22 in a member 23 which is also pivotally mounted, by means of a pin 24, on the side plate 10 of the machine. The member 23 is 30 provided with a rearwardly extending portion in which a series of gear teeth 25 are provided.

The platen 26 is mounted on a suitable shaft 27 which is journaled in bearing bushings 28 which are seated in the side frames 10 and 11. The 35 bearing bushings are held in place on the platen shaft 27 by means of snap washers 29 normally positioned in grooves in the projecting end portions of the platen shaft 27.

A rotatable member 30 is journaled on the 40 platen shaft 27 and is normally held in place thereon by means of a snap washer 31 which is seated in a suitable groove in the shaft 27. The rotatable member 30 has a portion provided with a plurality of gear teeth 32 which are engaged by 45 the gear teeth 25 of the member 23, the arrangement being such that when the member 23 is actuated, the motion thereof will be transmitted to the member 30, which as before stated, is journaled on the platen shaft 27.

The member 30 is also provided with a radially 50 extending pin 33 to the free end of which one end of a coil spring 34 is connected. The other end of the coil spring 34 is connected to a pin 35 secured in the side wall 10 of the frame. The 55 tension of the spring 34 normally tends to re-

turn the member 30 to its initial position after the key lever or levers is released.

The rotatable member 30 is also provided with a downwardly extending pin member 36, which is so positioned that the lower end thereof will, when the member 30 is rotated too far, encounter the pin 35 to which the coil spring 34 is connected. This arrangement is provided to limit the movement of the rotatable member 30, and is particularly desirable for such purpose when the platen is rapidly rotated or spun by the operator in the removal of a completed transcript from the machine.

The rotatable member 30 is also provided with a collar 37 on its periphery, which collar extends outwardly and encircles a ratchet like member 38 which is secured on the platen shaft 27. The ratchet like member 38 is provided with a plurality of working faces 39 which are disposed at right angles to a series of substantially radial faces 40 extending from the axis of the platen shaft 27. The faces 39 and 40 of the member 38 form, in conjunction with the internal surface of the collar portion 37 of the member 30, a series of wedge shaped pockets, in each of which a ball 41 is mounted.

The foregoing arrangement is such that when the member 30 is rotated in one direction, the balls 41 will abut against the substantially radial faces 40 of the member 30, and will then permit the member 30 to rotate freely, but upon the reversal of the direction of rotation, after a depressed lever or levers have been released, at least one of the balls 41 will be wedged in one of the pockets and will constrain the ratchet like member 38, and thereby the platen shaft 27, to be rotated.

A cover member 42 is provided having a collar portion 43 which overlaps the collar portion 37 of the member 30. This cover member 42 is maintained in position to protect and position the individual parts of the friction ratchet mechanism above described by means of a snap washer 44 which is mounted in a groove on the end of the platen shaft 27.

The operation of the mechanism above described will now be readily understood. Whenever one or more of the key levers 13 is depressed, the movement thereof will be communicated to the pivoted bracket arms 14 and 15 through the felt strip 17 and channel bar 16 which are supported at the front ends of said bracket arms 14 and 15. Said movement of the bracket arm 14 will then be communicated by the extension 20 thereof to the tooth 21 at the end thereof and thence to the pivoted member 23.

The movement of the pivoted member 23 will in turn be transmitted by the gear teeth 25 thereof to the rotatable member 30 by means of the gear teeth 32 carried thereby. The member 30 will thus be caused to rotate on the platen shaft 27, such movement being permitted by reason of the balls 41 being carried to the radial faces 40 of the ratchet like member 38. Said balls being thus brought to the larger ends of the respective pockets in which said balls are positioned, there will be no movement of the platen when the key lever is depressed.

However, upon the release of the key lever or levers, as the case may be, one or more of the balls 41 will be wedged in the tapered pockets provided between the working surfaces 39 of the ratchet like member 38 and the collar portion 37 of the member 30. The platen shaft 27 will then be rotated a short distance through the

tension of the spring 34, as well as the springs 18 which tend to return the bracket arms 14 and 15 to their initial positions.

The coil spring 34 not only assists the bracket arm springs 18, but it has been found in practice that the provision of an additional spring at this particular location, acting directly on the rotatable member 30, results in a more balanced operation of the parts, and enhances the freedom of operation of the machine.

I claim:

1. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be depressed when one or more of said key levers is depressed, pivoted bracket arms for supporting said bar, one of said bracket arms having an extending portion, a pivoted member having a recess engaged by a part of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a ratchet like member mounted on a projecting end portion of the platen shaft, said ratchet like member having surfaces shaped to provide, in conjunction with a portion of the rotatable member, a plurality of wedge shaped pockets, balls in said pockets adapted when the member on the platen shaft is rotated in one direction to be positioned in the wide portions of said pockets and when the member on the platen shaft is rotated in the other direction to wedge in said pockets to frictionally couple said rotatable member and said ratchet like member, and springs for returning the bracket arms to their normal raised positions and thereby actuating the platen.

2. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be depressed when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a ratchet like member mounted on a projecting end portion of the platen shaft, said ratchet like member having surfaces shaped to provide, in conjunction with a portion of the rotatable member, a plurality of wedge shaped pockets, balls in said pockets adapted when the member on the platen shaft is rotated in one direction to be positioned in the wide portions of said pockets and when the member on the platen shaft is rotated in the other direction to wedge in said pockets to frictionally couple said rotatable member and said ratchet like member, and springs for returning

the bracket arms to their normal raised positions and for simultaneously actuating the platen.

3. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be depressed when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid member, a ratchet like member mounted on a projecting end portion of the platen shaft, said ratchet like member having surfaces shaped to provide, in conjunction with a portion of the rotatable member, a plurality of wedge shaped pockets, balls in said pockets adapted when the member on the platen shaft is rotated in one direction to be positioned in the wide portions of said pockets and when the member on the platen shaft is rotated in the other direction to wedge in said pockets to frictionally couple said rotatable member and said ratchet like member, coil springs for returning the bracket arms to their normal positions, and a separate spring connected directly to the rotatable member on the platen shaft tending to return the same to its initial position.

4. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be actuated when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a ratchet like member mounted on a projecting end portion of the platen shaft, said ratchet like member having surfaces shaped to provide, in conjunction with a portion of the rotatable member, a plurality of wedge shaped pockets, balls in said pockets adapted when the member on the platen shaft is rotated in one direction to be positioned in the wide portions of said pockets and when the member on the platen shaft is rotated in the other direction to wedge in said pockets to frictionally couple said rotatable member and said ratchet like member, coil springs for returning the bracket arms to their normal raised positions, a separate spring connected directly to the rotatable member on the platen shaft tending to return the same to its initial position, and means for limiting the movement of said rotatable member.

5. In a typewriter of the character described

having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be depressed when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a frictional ratchet device adapted to permit the member on the platen shaft to be freely rotated in one direction and when the member on the platen shaft is rotated in the other direction to couple said rotatable member to the platen shaft and springs for returning the bracket arms to their normal raised positions.

6. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be actuated when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a frictional ratchet device adapted to permit the member on the platen shaft to be freely rotated in one direction and when the member on the platen shaft is rotated in the other direction to couple said rotatable member to the platen shaft, springs for returning the bracket arms to their normal raised positions, and a separate spring connected directly to the rotatable member on the platen shaft tending to return the same to its initial position and thereby actuate the platen.

7. In a typewriter of the character described having a plurality of key levers which may be operated separately, or of which two or more may be operated simultaneously, and having a platen adapted to be advanced upon the release of depressed key levers, means for actuating said platen comprising a bar extending across the machine beneath the key levers and adapted to be actuated when one or more of said key levers is depressed, pivoted bracket arms for supporting said bar, one of said bracket arms having an extending portion provided with a tooth, a pivoted member having a recess engaged by said tooth of the extending portion of said one bracket arm, said pivoted member having a plurality of gear teeth on an extending portion thereof, a rotatable member mounted on the platen shaft having a series of gear teeth engaged by the gear teeth of the aforesaid pivoted member, a frictional ratchet device adapted to permit the member on the platen shaft to be freely rotated in one direction and when the member on the platen shaft is rotated in the other direction to couple said rotatable member to the platen shaft, springs for returning the bracket arms to their normal raised positions, and a separate spring connected directly to the rotatable member on the platen shaft tending to return the same to its initial position and thereby actuate the platen.

75. In a typewriter of the character described

tional ratchet device adapted to permit the member on the platen shaft to be freely rotated in one direction and when the member on the platen shaft is rotated in the other direction to couple said rotatable member to the platen shaft, coil springs for returning the bracket arms to their normal raised positions, a separate spring connected directly to the rotatable member on the platen shaft tending to return the same to its initial position and thereby actuate the platen, and means for limiting the movement of said rotatable member.
